LOCKING BINDER

Filed Nov. 1, 1934

UNITED STATES PATENT OFFICE

2,017,934

LOCKING BINDER

Hubert Auburn, Mount Healthy, Ohio

Application November 1, 1934, Serial No. 751,063

8 Claims. (Cl. 129—24)

This invention relates to a binder metal including means for locking the pintle slides thereof in the operative or post holding position.

An object of the invention is to provide a simplified and very inexpensive means for accomplishing the above stated purpose.

Another object of the invention is to provide a slide locking means which is durable and effective, and which cannot become out of order, 10 by reason of wear or ordinary use or abuse.

A further object of the invention is to reduce to a minimum the number of moving and wearing parts in a lock equipped binder metal. The foregoing and other objects are attained by the 15 means described herein and disclosed in the accompanying drawing, in which:

Fig. 1 is a bottom perspective view of the improved binder metal, part being broken away.

Fig. 2 is a side view of the Fig. 1 device, the 20 Fig. 1 device being viewed from left to right.

Fig. 3 is a perspective view of a key such as may be employed to manipulate the locking means of the binder.

Fig. 4 is a bottom plan view showing a modified 25 form of the device.

Fig. 5 is a perspective view of a key for operating the locking means of the Fig. 4 device.

As stated in a previous paragraph, a purpose of the present invention is to minimize the number of moving parts in a lock equipped binder with the result that the binder metal as an 30 entirety may be very inexpensively manufactured and rendered practically free of servicing or replacement even after long periods of hard usage. 35 Devices of the general type herein disclosed, that is, binders equipped with pintle slide locks, are not broadly new, but so far as I am aware, such devices have included complicated locking means for the pintle slides which means required considerable space either in the back or in the cover 40 parts of the binder. It has always been a vexing problem to position the locks and mount them at locations in which they did not interfere with other portions of the binder structure, nor 45 add materially to the weight or bulk of the finished article. In the building of binder metals, it is desirable and in fact necessary, to maintain certain limits in size and weight so that the binder when completed, may readily be handled, 50 transported and stored in compartments of a minimum size.

With the foregoing in mind, a detailed description of the improved device will now be given.

In the drawing, 6 indicates a back member of 55 a desired size, which has its side edges turned

to provide a series of hinge eyes 7 whereby covers or heavy leaves 8 may be hingedly supported for movement relative to the binder back. The binder back may be either straight or arcuate in cross section, as desired, there being shown for the purposes of this description, a binder back which is straight in cross section. 5

Upon the top face 9 of the back member are fixed or rigidly mounted the pintle slide housings 10 and 12, said housings extending preferably 10 from one end of the back member to the other, in substantial parallelism with the side edges of member 6. The housings 10 and 12 may advantageously be formed by bending a length of sheet metal upon itself so as to provide a substantial U 15 shape. The housings thus formed are then fixed upon the back member with the edges 13 and 14 of the housings in closely abutting relationship with the upper face 9. The housings may be secured upon the back member by the use of 20 any suitable securing means there being shown, however, the bendable ears or lugs 15 and 16 which are integral with the housings, said lugs or ears being extended through properly located openings 17 and 18 of the back member and 25 thereafter turned over so as to clamp the housings upon the back member substantially as illustrated in Fig. 1.

Each of the housings 10 and 12 is adapted to receive therein a slide member 19 which carries one or more pintles 20 for anchoring one end 30 21 of a sheet holding post 22. In accordance with common practice, the pintle 20 is made integral with the slide member or bar 19, and the pintle is of sufficient length to extend through a trans- 35 verse bore 23 provided in one end of the sheet holding post. Between the end 24 of the pintle and the abutment 25 opposite thereto, is formed a space of sufficient length to permit complete withdrawal of the pintle from the bore in the 40 sheet holding post, so that the post may be removed bodily from association with the pintle slide and its associated housing. It will be understood that any desired number of pintles and sheet holding posts may constitute the binder 45 depending upon the sheet size or the number of perforations provided in the sheets. It will be observed that the lower edges 55 of the pintle slides are free to glide upon the upper face 9 of the back member, within the limits of the 50 housings 10 and 12. Each pintle preferably is provided with a suitable handle or extension 26 whereby the slide may be moved longitudinally relative to its housing. At least one end of the back member is provided with a depending end 55

plate or closure member 27, this member being preferably arcuate in formation so as to conform with the general configuration of a rear closure (not shown), of the binder when completed.

5 For a more detailed showing of one mode of attachment of a rear closure, reference is made to my issued Patent No. 1,891,037 which was issued December 13, 1932. If the rear of the binder is to be angular, the end plates may preferably 10 be made angular also, this being a matter of design only.

The end plate or plates 27 may be integral with the back member, or separately mounted thereon, as desired. The end plate 27 is provided with a pair of perforations 28 each of which is made in the shape of a keyhole for reception of the stem 29 and bit 30 of a key such as is illustrated, (Fig. 3). Pilot pins or studs 31 and 32 for the key, are extended outwardly from an 15 anchor block 33, said pins or studs being disposed substantially in axial alignment with the centers of the circular portions of the keyholes. The key of Fig. 3 has a longitudinal bore 34 for reception of a pilot pin upon insertion of the key into a keyhole. The mounting member 33 for the 20 pilot pins or studs is fixed upon the lower face of the back member with the use of any known fastening means, there being shown rivets or screws 35 for that purpose.

25 Intermediate the member 33 and the end piece 27 is a short spacer in the form of an outwardly extended block 36 which is fixed relative to the back member and the member 33. Block 36 and member 33 are so related as to form a short-stemmed T. Upon the exposed face 37 of block 36 there is riveted or otherwise fixed a resilient arm or leaf spring 38, which arm or spring has the lock bolts 39 and 40 fixed thereto. The bolts extend toward the back member, and through 30 perforations 41 and 42 thereof, so as to engage seats or notches 43 provided in the edges 55 of the pintle-slides. In the normal or closed condition of the binder structure, the bolts are seated in the notches 43 of their respective pintle slides. Upon inserting the key into one of the 35 keyholes 28 to an extent sufficient for disposition of the bit 30 above the spring or arm 38, the key may be rotated to compel downward flexing of the spring and the resultant withdrawal of its associated bolt from the seat or notch of the adjacent pintle slide. The slide thereupon may be withdrawn sufficiently to release one or more of the sheet holding posts. After the slide has been moved to the post releasing position, the 40 key may be removed from the keyhole, thereby permitting the lock bolt to ride upon the straight lower edge 55 of the pintle slide, until said slide is moved inwardly to the post holding position. Upon movement of the slide to such position, the 45 bolt will automatically be projected into the seat or notch 43, by reason of resiliency of the arm or spring which supports the bolt thereby to securely lock the pintle slide against further movement.

50 In the device of Figs. 1 and 2, the spring or bolt supporting arm 38 is disposed remote from the end piece 27, so that it is necessary to employ a relatively long key for manipulation of the bolts. This construction together with the 55 pilot pins or studs, serves to preclude picking of the lock with the use of makeshift instrumentalities. In the device of Fig. 4, the leaf spring or arm 138 is mounted upon a block or spacer 133 closely adjacent to the end plate 127, so that a short key 134 may be employed for lifting the

lock bolts 139 or 140. The keyholes 128, in the Fig. 4 structure, are not provided with pilot pins such as are found in the Fig. 1 device, wherefore suitable key guides 131 and 132 are mounted upon the binder back behind the spring member, 5 for reception of the end or pin 129 of the key. The bit 130 of said key may be curved or otherwise formed to fit a correspondingly shaped key-hole at 128. The slides 119 and their guides 110 will, of course, be identical with the slides and 10 guides shown in Fig. 1, except that the bolt notch or seat is located closer to the handles or extensions 126. The parts 160 and 170 correspond to the parts 6 and 7, respectively, of the Fig. 1 device. In both forms of the invention, the leaf 15 spring or resilient arm which supports the locking bolts, will be anchored at the mid-portion thereof, upon the back member, in spaced relationship to the back member.

It is to be understood that various modifications, and changes in the structural details may be made within the scope of the appended claims without departing from the spirit of the invention.

What is claimed is:

1. A binder metal comprising in combination a back member, a pair of spaced pintle slide housings mounted upon the back member, a pintle slide reciprocably supported within each of said housings, said slides each having a bolt seat 30 formed therein, an end plate on the back member and having formed therein two keyholes, one for each slide and a pair of slide bolting means disposed remotely from the end plate, one behind each keyhole, for entering its associated seat 35 and individually preventing movement of the slides, and releasable by means of a key inserted selectively into the keyholes and key pilot pins mounted longitudinally of the back member and extended substantially into the keyholes, to prevent insertion of a tool of sufficient thickness to unseat the slide bolting means.

2. A binder metal comprising in combination a back member, a pair of spaced pintle slide housings mounted upon the back member, a pintle slide reciprocably supported within each of said housings, an end plate on the back member, said plate having formed therein a pair of spaced keyholes, a key operated spring latch mounted 45 remotely from and behind each keyhole for individually preventing movement of the slides and releasable by means of a key inserted selectively into the keyholes and means spanning the space between the keyholes and the spring latches, positioned and proportioned to prevent insertion 50 of a tool large enough to actuate the spring latches at their remote positions behind the respective keyholes.

3. A binder metal comprising in combination a back member, a pair of spaced pintle slide housings mounted upon the back member, a pintle slide reciprocably supported within each of said housings, an end plate on the back member, said plate having formed therein a pair of spaced keyholes, and key operated means behind each keyhole 60 for individually preventing movement of the slides and releasable by means of a key inserted selectively into the keyholes, said key operated means including a single leaf spring fixed substantially at its mid-point transversely of the 65 back member and of the axes of the keyholes, and slide bolts fixed adjacent to opposite ends of said single leaf spring and arranged for bolting said pintle slides.

4. A binder metal comprising in combination 75

a back member, a pair of spaced pintle slide housings mounted upon the back member, a pintle slide reciprocably supported within each of said housings, an end plate on the back member said

5 plate having formed therein a pair of spaced keyholes, and key operated means behind each keyhole for individually preventing movement of the slides and releasable by means of a key inserted selectively into the keyholes, said key operated
10 means including a pair of movable slide bolts and a common mounting member for said bolts.

5. In combination, a plate-like back member for a binder, said back member including side edges and an angularly disposed end plate provided with a pair of spaced keyholes, the back member having formed therein a pair of bolt holes spaced from the end plate and located near the side edges of the back member, a pair of inverted U-shaped slide housings fixed upon one 15 face of the plate-like back member in substantial parallelism with the side edges thereof, the legs of each housing straddling one of the bolt holes, a pintle slide reciprocably supported in each of said slide housings, each pintle slide having an edge 20 slidable adjacent to the back member, said edges each having a bolt seat registrable with one bolt hole, locking means including a pair of pintle slide locking bolts one each of which normally extends through a bolt hole to engage the bolt seat 25 of its associated slide, a yielding bolt-supporting arm extending transversely of the back member from one bolt hole to the other, and located behind the end plate in spaced relation to the back member, in position to be contacted and moved by means of a key inserted into either one of the key holes in the end plate.

6. In combination, a plate-like back member for a binder, said back member including side edges and an angularly disposed end plate provided with a pair of spaced key holes, the back member having formed therein a pair of bolt holes spaced from the end plate and located near the side edges of the back member, a pair of inverted U-shaped slide housings fixed upon one 30 face of the plate-like back member in substantial parallelism with the side edges thereof, the legs of each housing straddling one of the bolt holes, a pintle slide reciprocably supported in each of said slide housings, each pintle slide having an edge 35 slidable adjacent to the back member, said edges each having a bolt seat registrable with one bolt hole, locking means including a pair of pintle slide locking bolts each one of which normally extends through a bolt hole to engage the bolt seat of its adjacent slide, a yielding bolt-supporting arm extending transversely 40 of the back member from one bolt hole to the other, and located behind the end plate in spaced relation to the back member, in position to be contacted and moved by means of a key inserted 45 into either one of the key holes in the end plate, a pilot pin associated with each key hole for guiding a key bit toward said yielding arm, and means for supporting both pilot pins longitudinally of the back member from the end plate to 50 the said yielding arm.

7. In combination, a plate-like back member for a binder, said back member including side edges and an angularly disposed end plate provided with a pair of spaced key holes, the back member having formed therein a pair of bolt holes spaced from the end plate and located near the side edges of the back member, a pair of inverted U-shaped slide housings fixed upon one face of the plate-like back member in substantial parallelism with the side edges thereof, the legs of each housing straddling one of the bolt holes, a pintle slide reciprocably supported in each of said slide housings, each pintle slide having an edge slidable adjacent to the back member, said edges each having a bolt seat registrable with one bolt hole, locking means including a pair of pintle slide locking bolts each one of which normally extends through a bolt hole to engage the bolt seat of its adjacent slide, a yielding bolt-supporting arm extending transversely of the back member from one bolt hole to the other, and located behind the end plate in spaced relation to the back member, in position to be contacted and moved by means of a key inserted into either one of the key holes in the end plate.

8. In combination, a plate-like back member for a binder, said back member including side edges and an angularly disposed end plate provided with a pair of spaced key holes, the back member having formed therein a pair of bolt holes spaced from the end plate and located near the side edges of the back member, a pair of inverted U-shaped slide housings fixed upon one face of the plate-like back member in substantial parallelism with the side edges thereof, the legs of each housing straddling one of the bolt holes, a pintle slide reciprocably supported in each of said slide housings, each pintle slide having an edge slidable adjacent to the back member, said edges each having a bolt seat registrable with one bolt hole, locking means including a pair of pintle slide locking bolts each one of which normally extends through a bolt hole to engage the bolt seat of its adjacent slide, a yielding bolt-supporting arm extending transversely of the back member from one bolt hole to the other, and located behind the end plate in spaced relation to the back member, in position to be contacted and moved by means of a key inserted into either one of the key holes in the end plate, a pilot pin associated with each key hole for guiding a key bit toward said yielding arm, and means for supporting both pilot pins longitudinally of the back member from the end plate to the said yielding arm.

HUBERT AUBURN.
